UNITED STATES PATENT OFFICE.

HARRY DE WALLACE, OF SYRACUSE, NEW YORK.

FLUSH-VALVE-OPERATING MECHANISM.

Application filed July 9, 1926. Serial No. 121,472.

This invention relates to flush valve operating mechanism, designed particularly for use in connection with china flush tanks, and has for its object to provide a novel form of sleeve for mounting in the usual opening in the wall of the tank, whereby the entire mechanism may be readily, quickly, and rigidly clamped to the wall, by means of a single threaded member. A further object 10 is to provide a novel arrangement of the china operating parts whereby the handle and escutcheon comprise a single part and whereby the operating shaft may be permanently secured to the china member and may 15 be inserted inwardly through the sleeve, and detachably connected to a crank member that actuates the valve lift, by simple clinching means. And a further object is to generally improve and simplify the mechanism, 20 to the end that fewer parts, and less time, labor and expensive operations are required, for manufacturing, assembling and applying the said mechanism, than heretofore.

I attain these objects by the means set forth 25 in the detailed description which follows, and as illustrated by the accompanying drawing, in which—

Figure 1 is a top end view of a flush tank with the cover removed. Fig. 2 is a broken 30 side elevation of the same. Fig. 3 is a broken end elevation of the tank. Fig. 4 is a horizontal section, taken on line 4—4 of Fig. 2. Fig. 5 is a view of the handle shaft. And Fig. 6 is respectively an end and a side view 35 of the crank member carried by the handle shaft.

In the drawing, 2 represents a china flush tank, which may be supplied with the flushing water by a pipe 3, the water being 40 delivered by said pipe to a ball-cock 4, and the latter being controlled by the usual float 5. The discharge of the water for flushing purposes is effected by an ordinary valve 6, which controls the usual bottom outlet (not 45 shown). The valve 6 is lifted away from its seat by a rod 6', whose upper end connects with one end of a rockable lever 7, as shown in Figs. 1, 3 and 4. The opposite end of the lever 7 is formed with a crank-portion 7'. 50 The lever 7 is operatively supported by similar spaced perforated lugs 8, which may be integral parts of a bracket 8, the latter being mounted horizontally on the inner front wall of the tank 2. The bracket 8 is 55 formed with a flange-hub 8^a, which loosely engages a molded opening 2' of the tank,

as best seen in Figs. 3 and 4. The hub 8^a is preferably formed with a smooth bore, which loosely receives the barrel of a sleeve 9 that extends through the opening 2' of the 60 tank. The outer end of the sleeve 9 is formed with an annular flange 9', which is preferably larger in diameter than the opening 2', and is arranged to seat against the outer face of the tank wall when the fitting is applied thereto (see Fig. 4). Adjoining the flange 9', the sleeve is formed with an enlargement 9^a, which substantially fills the opening 2' adjacent the said flange, like the hub 8^a. Beyond the enlargement 9^a the 65 barrel of the sleeve is preferably externally threaded, as at 9^b. This threaded portion passes through the hub 8^a of the bracket and its projecting inner end is fitted with a nut 10, which engages the bracket, and together 70 with the sleeve provides the sole means for clamping the valve operating mechanism to the tank. The sleeve 9 has a smooth bore, in which is loosely journaled a shaft or rod 12, by which the lever 7 is rocked for opening 75 the flush valve 6. The shaft 12 projects beyond the opposite ends of the sleeve 9, its inner end preferably being square and split, as at 12', and upon this split portion is 80 mounted a crank member 13, as best shown 85 in Figs. 4 and 5. One arm of the crank 13 is formed with a loop or eye 13', the opening of the latter being preferably square to conform to the shaft. The other arm of the member 13 extends rearwardly beneath the 90 crank portions 7' of the lift rod. The outer end 12^a of shaft 12 is also shown square, and this portion is preferably permanently embedded in a molded socket 14' of a china member 14, the latter combining in one part 95 an escutcheon 14^a, an ornamental spherical portion 14^b, and a pending handle 14^c, by which the shaft 12 and crank 13 are rocked for opening the valve 6. The square portion 12^a may be secured in the socket 14' by any 100 suitable cement, as litharge, or the like. The escutcheon 14^a is preferably formed with a central cavity or recess 14^d, which receives and conceals the flange 9' of the sleeve. The flange 9' and the recess 14^d are preferably 105 so constructed that when the device is assembled, as shown in Fig. 4, the part 14^a is held clear of and may rotate freely without touching or chafing the tank 2.

To apply my device to a tank, the barrel of the sleeve 9 is preferably first inserted 110 inwardly through the opening 2' of the

tank, the bracket 8 is next placed in position against the inner side of the tank with the hub 8^a loosely telescoping the said opening and the threaded portion 9^b of the sleeve. 5 The nut 10 is then screwed on to the sleeve and tightened up for rigidly clamping the flange 9' and the bracket 8, to the wall of the tank. The shaft 12 which is preferably first permanently secured to the china part 10 14, is next inserted inwardly through the sleeve until its split inner end projects beyond the corresponding end of the sleeve. The crank member 13 is then applied and the split portion of the shaft is spread and 15 clinched against the outer face of the loop 13', for holding the shaft and related parts in place, as shown in Figs. 3 and 4. The square portion 12' is preferably slightly reduced in order to provide a shoulder 20 against which the inner face of the loop 13 seats, as shown in Figs. 4 and 5. The shaft 12 and the member 14 may be readily and quickly removed by simply unclinching the split end of the shaft.

25 My flush valve operating mechanism is extremely simple, has but few parts, and requires but little machine work in order to prepare the parts for use. By constructing the parts as herein shown and described, 30 but one threaded connection is required for mounting and holding the mechanism in place, and by molding the escutcheon, knob, and handle in one part (14) and embedding the shaft 12 in the said china member, 35 greatly facilitates the assembling, applying and removing of the mechanism.

Having thus described my invention, what I claim, is—

40 1. A flush valve operating mechanism including a lever supporting bracket engageable with a side face of a wall of a tank and having a hub formed to project loosely and partly within one end of a transverse open-

ing in said wall of the tank, a sleeve having a threaded end extending through the 45 bracket and its hub, an integral flange on the opposite end of the sleeve engageable with the opposite side face of said tank wall and having a hub of reduced diameter extending partly within the opposite end of 50 the opening, the inner ends of the hubs being spaced so as to leave free space between the part of the sleeve between the hubs and the wall defining the said transverse opening in the tank, a shaft extending through the 55 sleeve, a handle on the opposite end of the shaft having an escutcheon extending over the flange and in encircling relation to the periphery thereof, a nut on the threaded end of the sleeve engageable with the 60 bracket, and a crank on the other end of the shaft.

2. In a flush valve operating mechanism, a sleeve formed to extend through a perforation in a tank wall and having an integral flange on one of its ends formed with an inwardly projecting hub, the flange being engageable with one face of the tank wall and the hub being engageable in the wall perforation, a lever supporting bracket 65 engageable with the opposite face of the tank wall and perforated to receive the opposite end of the sleeve and having a hub engaging the wall defining the perforation, said hubs having their inner ends spaced apart and conjointly acting to hold the center of the sleeve spaced from the wall defining the perforation, means on the said opposite end of the sleeve to hold the bracket against said opposite face of the 70 tank wall, a shaft extending through the sleeve, a handle on one end of the shaft and a crank on the other end of the shaft.

75 In testimony whereof I affix my signature.

HARRY DE WALLACE.
